SOUND-PRODUCING DEVICE.

Application filed January 2, 1925. Serial No. 42.

This invention relates to sound producing devices and more particularly to an automatic sound producing device or "voice" of the type now commonly used in dolls and other toys for simulating the word "Mama" or other characteristic cry.

My present improvements are more particularly directed for use in connection with a voice or device of that general construction wherein there is provided an air chamber and a gravity movable weighty member for expelling air from said chamber through a sound producing reed. In such devices, the emission of the sound is intermittently interrupted and controlled in the movement of the air expelling member by means of cooperatively related parts, whereby the sound is properly articulated. It has been the common practice to fixedly secure one of these parts relatively to the other, and therefore it has been necessary to provide an enclosing casing or housing of comparatively great length in order to secure the required stroke or length of movement of the weighty air expelling member.

It is one of the primary objects of my invention to provide a sound emission controlling means in which the two coacting parts thereof are mounted and arranged within a casing or housing for independent relative movement in such manner that it is possible to enclose said parts within a relatively short casing, and yet insure the complete articulation of the word syllables.

In a preferred embodiment of the device, one of the relatively movable sound control parts is axially positioned within the air chamber and constitutes a guide for the weighty air expelling member and the other sound control part.

It is another object of my invention to provide a very simple construction and arrangement of the several elements whereby they may be rapidly assembled in cooperative relation with each other, thereby reducing production cost to a minimum.

With the above and other objects in view, the invention consists in the improved sound producing device and in the form, construction and relative arrangement of its several parts as will be hereinafter more fully described, illustrated in the accompanying drawings and subsequently incorporated in the subjoined claims.

In the drawings wherein I have illustrated

one simple and practical embodiment of the invention, and in which similar reference characters designate corresponding parts throughout the several views,

Figure 1 is a vertical sectional view, illustrating one embodiment of my present improvements and showing the relative positions of the parts at the start of the gravity descent of the weighty air expelling member. 60

Figure 2 is a similar view showing the 65 relative positions of the parts at an intermediate stage of the air expelling movement of said member,

Figure 3 is a vertical sectional view showing the relative positions of the parts at the 70 end of the air expelling movement of the weighty member,

Figure 4 is a plan view with the end cap or cover of the casing removed, as indicated by the line 4—4 of Figure 2, and 75

Figure 5 is a horizontal sectional view taken on the line 5—5 of Figure 2.

For purposes of illustration, in the accompanying drawings I have shown the operative parts of the device enclosed within 80 a cylindrical housing or casing having a body wall 5, which may consist of a length of cardboard tubing, the opposite ends of which are closed by the metal caps 6 and 7 respectively. As herein shown, the cap 6 85 is provided with a marginal flange for clamping engagement with one end edge of a tubular flexible bellows wall 8, which is turned over the end edge of the casing wall 5. The other metal cap or cover 7 is provided with a plurality of sound emission openings 9 therein. To the other end edge of the tubular bellows wall 8 a weighty gravity movable head 10 is suitably fixed, said head, as herein shown, consisting of a 90 disc of lead or other metal, centrally provided with a concentric sleeve 11 projecting from one side thereof. The wall of this sleeve intermediate of its ends and at diametrically opposite sides thereof is provided 100 with the sound emission openings 12 therein. The extremity of the sleeve wall is reduced in thickness to receive a disc 13, which is suitably fixed thereon and is of slightly less diameter than the internal diameter of the 105 casing wall 5, so as to permit of the free and un retarded movement of the member 10, while preventing any substantial angular tilting movement out of concentric relation with said casing wall. This disc 13 is also 110

provided with a suitable number of openings 14 so that the sound may escape therethrough into the end of the casing and finally pass through the openings 9 in the 5 cover plate 7.

A tube 15 is loosely engaged through the sleeve 11, the external diameter of this tube being sufficiently less than the internal diameter of said sleeve to provide a narrow 10 passage 16 between the walls of said sleeve and tube. It will be noted that said tube 15 is of materially less length than the length of the casing wall 5, while of slightly 15 greater length than the distance between the casing cover 6 and the weighty head 10, when the flexible wall 8 of the bellows is expanded so that the said tube will never become entirely disengaged from the sleeve 11.

Within one end of the tube 15 a sound 20 producing reed 17 is suitably mounted and the end edge of the tube wall adjacent the egress end of the reed is provided with one or more notches or recesses 18, through which air may enter into the interior of said 25 tube from the bellows chamber.

The wall of the tube 15 adjacent to its opposite end is provided with diametrically opposed circumferentially extending openings 19 therein, which, as shown in Figure 30 5 of the drawings, are of somewhat greater circumferential extent than the emission openings 12 in the wall of the sleeve 11, so that, although the tube 15 may rotate within the sleeve and the positions of the openings 19, with respect to the openings 12 may 35 vary, there will at all times be an appreciable portion of the area of the openings 19 in line with the openings 12 so that in the relative longitudinal movement of the 40 sleeve and tube, said openings will register for the emission of sound therethrough. This latter end of the tube 15 beyond the openings 19 is closed by means of a suitable plug inserted therein as indicated at 20.

45 In the operation of the device above described, assuming that the bellows has been fully expanded and the parts are in the relative positions seen in Figure 1 of the drawings, the tube 15 and weighty member 10 50 move downwardly as a unit under the action of gravity. However, owing to the body of air contained within the bellows chamber and which must be compressed by the weighty member 10, the movement of this 55 member is relatively slow. Therefore, initially the tube 15 will move faster than the member 10 and drop by gravity through the sleeve 11 until it comes to a position of rest upon the cover or cap 6 of the casing.

60 During this independent relative gravity movement of the tube 15, air is of course forced under pressure by the member 10 through reed 17 and the sound thus produced passes through openings 19 in the tube wall 65 and downwardly through the passage 16 and

the openings 12 into the space between the member 10 and the disc 13, such sound passing through the openings 14 in the disc and openings 9 in the metal cover 7, thus simulating the sound of the letter "m". When 70 the tube finally rests upon the cap 6, the openings 19 are in registration with the openings 12 so that sound in greater volume is emitted through these registering openings to simulate the sound of the letter "a", 75 thus completing the sound of the first syllable "ma".

In the continued gravity movement of the weighty member 10 relative to the now stationary tube 15, the openings 12 move out 80 of registration with the openings 19 in the tube wall so that the larger volume of sound is cut off and sound again escapes in restricted volume through said openings 19 and the passage 16 and openings 12, thereby 85 again simulating the sound of the letter "m" and when the end of the sleeve 11 moves entirely below the openings 19, sound is again emitted in larger volume through said openings to simulate the letter "a" for a 90 second time, and thereby complete the sounding of the second syllable "ma". The sounding of the final letter "a" continues until the member 10 reaches its final position of rest, as shown in Figure 3 of the drawings. 95 Thus it will be seen that the sounding of the infant cry "Ma ma" is simulated in a very realistic manner.

In the functioning of the parts, it will 100 be observed from the foregoing description, that the openings 19 in the wall of the gravity movable tube operate at spaced intervals in the gravity descent of the weighty member 10 to twice emit the larger volume of sound to simulate the letter "a". Thus, 105 I am enabled in a relatively short stroke of air expelling movement of the member 10 to effect the desired articulation of the sound by permitting of the axial movement 110 of the tube 15 and causing the single pair of openings 19 therein to twice subserve the desired function. It will be apparent that if the tube 15 were fixed in relation to the movable member 10 it will be necessary to 115 provide for an appreciably greater extent of movement of this weighty member. It will accordingly be appreciated that my present improvements are of considerable importance in that they permit of the mounting 120 and arrangement of the operative parts of the device within a casing of comparatively short length so that the device can be mounted or arranged in dolls of small size.

125 From the foregoing description considered in connection with the accompanying drawings, the construction, mounting and arrangement of the several parts of my present improvements will be clearly understood. It will be seen that I have provided a sound producing device or "voice", the parts of 130

which are of very simple construction, easily assembled and positive and efficient in the performance of their functions. While in the present instance I have shown the air compression chamber in the form of a collapsible bellows, it will be understood that insofar as the operation of the sound emission control means is concerned, that this is not essential, and said control means might 10 be employed in connection with any other desired arrangement of the gravity operable air expelling means. Further, while I have disclosed herein a construction of the relatively movable parts of the sound control means which I have found to be satisfactory in practical use, it will nevertheless be understood that these parts likewise may be susceptible of considerable modification without materially effecting the results produced. Accordingly, I reserve the privilege 20 of incorporating my present improvements in all such alternative structural forms as may be fairly embodied within the spirit and scope of the invention as claimed.

25 I claim:

1. In a sound producing device, an air receiving chamber and a weighty gravity movable member for expelling air from said chamber, a sound producing reed through 30 which the air is expelled, and means for articulating the emission of sound produced by said reed, including parts each having coacting sound emission controlling apertures and each movable relative to the other 35 and with respect to said chamber in the direction of movement of said weighty member.

2. In a sound producing device, an air receiving chamber and a weighty gravity 40 movable member for expelling air from said chamber, a sound producing reed through which the air is expelled, and means for articulating the emission of sound produced by said reed including an apertured part on 45 said weighty member and an independent sound control member having a sound emission aperture coacting with said apertured part and movable by gravity independently of said weighty member.

50 3. In a sound producing device, an air receiving chamber and a weighty gravity movable member for expelling air from said chamber, a sound producing reed through which the air is expelled, and means for articulating the emission of sound produced by said reed including an apertured part carried by said weighty member, and a sound emission controlling element having 55 an emission aperture to coact with the aperture in said part and loosely extending through said weighty member for gravity movement independently thereof.

60 4. In a sound producing device, an air receiving chamber and a weighty gravity movable member for expelling air from said

chamber, a sound producing reed through which the air is expelled, and means for articulating the emission of sound produced by said reed including an apertured part carried by said weighty member, and a sound emission controlling member independent of said weighty member and co-operatively associated with said apertured part and bodily movable by gravity with respect thereto and independently of said weighty member to control the emission of sound through said apertured part.

5. A sound producing device, comprising a casing having an air chamber therein and a weighty gravity movable member for expelling air from said chamber, a reed through which the air is expelled and means for articulating the sound produced by said reed including an apertured part carried by said weighty member, and an apertured sound emission controlling element independent of said weighty member and mounted within the casing for movement by gravity between the ends thereof, the apertures of said part and said element coacting to control the emission of sound.

6. A sound producing device including a casing, a sound producing reed, a weighty member longitudinally movable by gravity in said casing to expel air through said reed, said weighty member having a valve part, and a gravity movable sound emission controlling element, independent of said weighty member, extending longitudinally of the casing and of less length than the distance between the casing ends slidably engaged with said valve part on said weighty member for interrupting the emission of sound through said valve part.

7. A sound producing device, comprising a casing having an air chamber therein and a weighty member longitudinally movable in the casing to expel air from said chamber, said weighty member having a sleeve thereon provided in its wall with a sound emission aperture, a gravity movable tube extending loosely through said sleeve and of less length than the casing, a reed carried by said tube through which the air is expelled, and the wall of said tube having an opening therein to coact with the opening in said sleeve wall and effect the articulation of the sound in the relative gravity movement of the weighty member and the tube.

8. In a sound producing device, a casing having an air chamber therein and a weighty gravity movable member to expel air from said chamber, said member having a sleeve provided with a sound emission aperture in its wall and a tube loosely engaged through said sleeve and of less length than the distance between the casing ends, a reed mounted in one end of said tube through which the air is expelled, the wall of said tube adjacent its other end having an opening there-

in, and said tube moving by gravity relative to said weighty member in the initial air expelling movement thereof, whereby the opening in the tube wall is caused to register 5 with the aperture in the wall of said sleeve, and said sleeve cooperating with the opening in said tube wall in the continued gravity movement of the air expelling member, whereby the articulated emission of the 10 sound is effected.

9. In a sound producing device, an air receiving chamber and a weighty gravity movable member for expelling air from said chamber, a sound producing reed through 15 which the air is expelled, and means for articulating the emission of sound produced by said reed including an apertured part carried by said weighty member, and a sound emission controlling element having an emission aperture to coact with the aperture in said part, said element being movable by gravity independent of said weighty member during the initial air expelling movement of said member and having a part adapted to 20 engage one end of the casing and maintain said element in a relatively stationary position during the remaining air expelling movement of said member.

10. In a sound producing device, an air receiving chamber and a weighty gravity movable member for expelling air from said chamber, a sound producing reed through 30 which the air is expelled, means for articulating the emission of sound produced by 35 said reed including an apertured part carried by said weighty member, a sound emission controlling element having an emission aperture to coact with the aperture in said part and movable by gravity independently 40 of said weighty member during the initial portion of the air expelling movement of the latter, and a relatively fixed part limiting such gravity movement of the sound emission controlling element and maintaining the 45 same in a relatively stationary position during the remaining air expelling movement of said member.

11. In a sound producing device, an air receiving chamber and a weighty gravity movable member for expelling air from said chamber, a sound producing reed through 50 which the air is expelled, means for articulating the emission of the sound produced by said reed including parts each having 55 sound emission apertures and each movable relative to the other and with respect to said chamber in the direction of movement of said weighty member, and means for preventing any substantial lateral tilting motion 60 of said member with respect to the direction of its air expelling movement.

12. In a sound producing device, an air chamber, a sounding reed, co-axially associated parts movable by gravity independently of each other, one of said parts con-

stituting a head for one end of the air chamber and operating in its gravity movement to expel air therefrom through said reed, said parts coacting in their relative gravity movement to control the emission of the sound produced by said reed, and said air chamber having a head at its other end constituting a stop to limit the gravity movement of the other of said parts and hold the same relatively stationary during the continued gravity movement of the first named part.

13. In a sound producing device, an air chamber having a gravity movable head at one end and a relatively fixed head at its 80 other end, a sound producing reed through which air is expelled from said chamber in the gravity movement of said first named head in one direction, a second gravity movable member co-axially associated with said gravity movable chamber head and movable independently thereof, said chamber head and member having coacting means controlling the emission of the sound, and said member adapted to engage the fixed head of said chamber to limit the independent gravity movement of said member and hold the same stationary during the continued gravity movement of the chamber head.

14. In a sound producing device, a casing, a bellows enclosed within said casing having a fixed head at one end and a gravity movable head at its other end, a sound producing reed through which air is expelled from the bellows by the gravity movement of the latter head in one direction, a member having independent gravity movement through said movable bellows head, and the fixed head of said bellows constituting a stop limiting such independent gravity movement of said member to hold the same relatively stationary during the continued gravity movement of said bellows head, and said bellows head and member having coacting parts controlling the emission of the sound produced by said reed.

15. In a sound producing device, an air chamber, a gravity movable member constituting a head for one end of said chamber, a sounding reed through which the air is expelled from the chamber in the gravity movement of said head in one direction, a member having independent gravity movement relative to said chamber head, said head and member coacting to control the emission of the sound produced, and means adapted to be engaged by said member to limit the gravity movement thereof and constituting a stop to support said member in a relatively stationary position during the continued gravity movement of the air chamber head.

16. In a sound producing device, a casing having an air chamber therein, a sounding reed, and two members each reciprocal by 130

gravity relative to the other and movable within said casing along a common axis, said members having coacting means to control the emission of sound in the relative recipro-

5 cation of said members, one of said members during its reciprocation in one direction causing the passage of air through said reed and the sound emission controlling means thereof twice cooperating with the sound

emission controlling means of the other 10 member in the relative reciprocation of said members to thereby effect an articulated emission of the sound.

In testimony that I claim the foregoing as my invention, I have signed my name 15 hereto.

LEO J. GRUBMAN.
